CLAIM

The ornamental design for a speaker front panel, as shown and described.

DESCRIPTION

FIG. 1 is a front elevational view of a speaker front panel showing our new design;

FIG. 2 is a right elevational view thereof;

FIG. 3 is a left elevational view thereof;

FIG. 4 is a top plan view thereof;

FIG. 5 is a bottom plan view thereof; and,

FIG. 6 is a front, top, and right side perspective view thereof.

The broken lines shown in FIGS. 1-6 are for illustrative purposes only and form no part of the claimed design.

The ornamental design for a speaker front panel, as shown and described.
